UNITED STATES PATENT OFFICE.

WILLIAM SCHALK, OF WEST ALLIS, WISCONSIN.

BOX.

1,152,054.

Specification of Letters Patent.

Patented Aug. 31, 1915.

Application filed October 16, 1914. Serial No. 866,903.

To all whom it may concern:

Be it known that I, WILLIAM SCHALK, a citizen of the United States, and resident of West Allis, in the county of Milwaukee and State of Wisconsin, have invented new and useful Improvements in Boxes, of which the following is a description, reference being had to the accompanying drawings, which are a part of this specification.

10 The invention relates to boxes.

The invention designs more particularly to provide a foldable shipping box. One of the uses of a box of this kind is in the shipping of leaf tobacco. Formerly tobacco was shipped in boxes which could not be readily opened to inspection and the present device is designed to obviate this difficulty by providing a foldable box so that the ends, sides and top of the box may be thrown down and out of the way to permit a thorough inspection of the tobacco. Furthermore, it is necessary to have a strong box but the tobacco itself should not be brought into contact with the metallic reinforcement and therefore the box has been constructed to have an interior lining of wood or other suitable material which also forms the box sections and to have the metallic reinforcement and binding placed upon the outside of the box.

20 The invention further designs to provide a box made up of foldable sections, each of said sections being provided with metallic reinforcement which is pivotally connected to the metallic reinforcement of the adjacent section and means for fastening the reinforcing means together.

25 The invention further designs to provide means for fastening the box sections together by means adapted to be connected to the reinforcing members.

30 The invention further designs to provide a new and improved form of box.

In the drawings, Figure 1 is an end view of the box; Fig. 2 is a view of one side thereof; Fig. 3 is a plan view of the box; the cover being raised; Fig. 4 is a section taken on the line 4—4 of Fig. 2; Fig. 5 is a section taken on the line 5—5 of Fig. 2; Fig. 6 is a view of the box in unfolded condition.

35 The box comprises a bottom 7, sides 8 hinged thereto, top 9 hinged to one of the sides, ends 10 hinged at either end of the bottom 7 and means for reinforcing and connecting these sections together. The top, bottom and sides are preferably made of solid pieces of wood or other material while

the ends are made of a plurality of pieces 11 spaced apart to provide for air space as in the use of the box in connection with tobacco it is necessary that proper ventilation be provided.

40 The bottom 7 is provided with a plurality of reinforcing members or bars 12 preferably of sheet metal which are secured within recesses 13 extending transversely of the bottom. The sides 8 are likewise provided with a plurality of reinforcing members 14 similar to the bars 12 and are secured within transverse recesses 15 therein. The bars 12 on the bottom section 7 extend outwardly and are hinged to the extensions 16 of the bars 14 of the side sections and the top 9 which is also provided with bars 17 secured within transverse recesses 18 is hinged to one of the sides 8 in the same manner as the bottom section is attached to the sides. Thus it will be noted that the reinforcing members or bars 12, 14 and 17 form continuous bands extending around the top, bottom and sides of the box and secured within recesses 80 therein and to each other.

45 The pieces 11 are connected together to form the end sections 10 by a plurality of reinforcing bars 19 which are secured in recesses 20 in said pieces extending transversely thereof and these bars are hingedly secured to the extensions 21 which are riveted to the bars 12 and extend at an angle thereto. Extensions 22 are riveted to the bars 19 and extend outwardly from the ends 90 of the box and have apertures 23 therein. The end edges of the sides 8 have recesses 24 therein to receive the extensions 22 of the bars and apertures 25 adjacent said recesses and extending lengthwise of the sides to a 95 position adjacent the transverse bands 14. Threaded nuts 26 having lugs 27 thereon are fastened to the bands 14 adjacent said apertures 25, the lugs 27 permitting the nuts 26 to be riveted to the bands as shown in Fig. 4. 100 Bolts or other suitable fastening means 28 pass through the apertures 23, 25 and into the nuts 26 which being embedded in recesses 29 in the sides 8 connect the bands 22 with the bands 14 and consequently the ends 105 10 to the sides 8.

50 The top 9 has apertures 30 adjacent apertures 31 in the bands 17 which apertures are adapted to receive screw bolts 32 or other suitable fastening means which pass through threaded plates 33 secured in recesses 34 on the edge of one of the side sections 8 and

riveted to the ends of the bars 14. The screw bolts 32 thus serve to connect the bands 17 and 14 together and also secure the top to the side.

5 Strips 35 are secured on the inner side of the bottom 7 adjacent the ends and serve as stops for the ends 10 when they are in position and triangular shaped stop strips 36 on the ends 10 and sides 8 serve to keep the ends 10 and sides in proper position when the box is assembled.

In the use of the box the sides 8 are turned up against the bottom 7 and the ends 10 are secured to the sides by the bolts 28 which 15 pass through the extensions 22 and into the nuts 26 in the sides 8. The box is then packed and the top is then secured to the opposite side section 8 by the bolts 32. If it is desired to inspect the contents of the box the 20 bolts 28 are removed and the ends dropped down and the bolts 32 removed and the top and sides dropped down leaving the contents of the box resting upon the bottom 7 open to inspection.

25 From the foregoing description it will be noted that the interior of the box is wholly of wood or other suitable material and that the exterior is provided with metallic reinforcing members which are disposed in recesses in the respective sections to provide a smooth outer surface, that these members also serve to connect the different sections of the foldable box together and that the fastening means for holding the sections together are also connected to these members so that the reinforcing means with its connections form a foldable skeleton framework to which the foldable sections are attached.

40 The invention is not to be restricted to the details of construction herein set forth but may be varied so as to be within the scope of appended claims.

What I claim as my invention is:

45 1. A box comprising a solid top, bottom, side and end sections, reinforcing means secured to said sections, hinged connections between the reinforcing means on the bottom section and the side sections, hinged connections between the reinforcing means on the top section and one of the side sections, re-

inforcing means secured to said end sections and hingedly connected to the reinforcing means on the bottom section, means for connecting the reinforcing means on the top section to the reinforcing means on the opposite side section, and means for connecting the reinforcing means on the end sections to the reinforcing means on the side sections. 55

2. A box comprising foldable top, bottom, 60 side and end sections, reinforcing members secured to said sections, hinged connections between the reinforcing members on the bottom section and the side sections, hinged connections between the reinforcing members on the top section and one of the side sections, hinged connections between the reinforcing members on the bottom section and the end sections, and means secured to the reinforcing members on certain of the sections 65 coöperating with means passing through the reinforcing members on the sections disposed adjacent thereto to secure the sections in assembled position. 70

3. A box comprising foldable top, bottom, 75 side and end sections, reinforcing members secured to said sections, hinged connections between the reinforcing members on the bottom section and the side sections, hinged connections between the reinforcing members on the top section and one of the side sections, hinged connections between the reinforcing members on the bottom section and the end sections, nuts secured to the reinforcing members adjacent the sides of the 80 side sections and adjacent the top of one of the side sections, said side sections having apertures therein in line with said nuts, and bolts passing through apertures in the reinforcing members of the end and top sections 85 and through the apertures in the sides of the side sections and in the top of one of the side sections for locking engagement with said nuts to secure the sections in assembled 90 position. 95

In testimony whereof, I affix my signature, in presence of two witnesses.

WILLIAM SCHALK.
